RHEOSTAT WINDING MACHINE

Dominic J. Holleran, Irvington, N. J., assignor
to Hardwick, Hindle, Inc., Newark, N. J., a
corporation of New Jersey

Application December 21, 1936, Serial No. 116,933

14 Claims. (Cl. 242—4)

The present invention relates to a rheostat winding machine, particularly for the winding of a solid or continuous ring of toroidal shape, and while the machine is primarily intended for the winding of the ceramic core of a rheostat it will be understood that the invention is applicable to the winding of other objects presenting similar problems and requirements.

An object of the invention is to provide a machine which will be adjustable for the winding of solid continuous ring cores of any diameters between the minimum and maximum diameter limits of the machine, and which will also wind such rings with any desired size, gauge or type of wire or other winding material, ranging for instance from one mill to $\frac{1}{8}$ inch flat ribbon wire in the case of rheostats, and further to provide for an infinite variation of pitch or leads within the minimum and maximum limits of the machine, ranging for instance between 15 to 3000 turns or convolutions to the ring.

Another object is to provide a machine of this character which will be extremely accurate in operation and in predetermination of the desired winding, will be rapid in operation, and will not require highly skilled operators for tending to the machine.

In winding rheostats great precision is necessary so that the winding will be evenly spaced with the proper pitch or lead between the turns, and the windings must be sufficiently tight upon the ceramic core so that they will lie flat upon the core surfaces and will not become displaced. In accomplishing this there must be a tension or pull upon the wire as it is being wound sufficient to bend the wire sharply about the corners of the core at the same time pulling it in flat relation to the core surfaces, and it is an object of the invention to provide means whereby such tensional pull may be provided, and which may be adjusted to accomodate wires of greatly varying size and bending characteristics.

A further object of the invention is to provide bobbin means mounted upon the winding shuttle which can carry sufficient wire to wind a number of rheostats before requiring respooling of the bobbin, thereby simplifying the operation of the machine and greatly speeding up its production. In the case of winding rheostats, it is proposed to provide wire upon the bobbin sufficient to wind on the average of six rheostat cores (depending on the size of ring, wire and pitch) before respooling the bobbin.

It is further proposed to provide bobbin respooling means by which bobbins may be re-

spooled during the winding of the rheostats, and further to provide counter means in connection with the respooling means to predetermine the amount of wire wound on the bobbin, thereby eliminating waste of wire through the spooling of short lengths.

Another object of the invention is to provide control means whereby any part of the machine may be started or stopped, operated or adjusted by hand, and further to provide automatic means for stopping the machine at the end of each ring winding operation, thereby eliminating the necessity of constantly watching the operation.

The machine according to the invention is particularly characterized by its compactness, and simplicity and design and operation, as well as the ease and precision with which it may be adjusted for the various size rings, pitches or leads, and tensions for different sizes and character of wires. In particular it is proposed to provide pitch adjusting means which can be set to a predetermined pitch before the winding operation starts, or if desired can be changed even while the machine is in operation. It is proposed in connection with the tension adjusting means to provide a calibrated dial on the winding shuttle by which the proper tension may be predetermined and maintained.

With the above and other objects in view, an embodiment of the invention is shown in the accompanying drawings, and this embodiment will be hereinafter more fully described with reference thereto, and the invention will be finally pointed out in the claims.

In the drawings:

Fig. 1 is a front elevation of the winding machine, according to the exemplary illustrated embodiment of the invention.

Fig. 2 is a top plan view thereof, the ring holding means, which is shown in its operative ring engaging position in Fig. 1, being shown in disengaged position and partially broken away.

Fig. 3 is an end elevation looking from the right hand end of the machine as shown in Fig. 1.

Fig. 4 is a vertical sectional view, taken along the line 4—4 of Fig. 2, this figure, and Figs. 5 to 20, being on a larger scale than Figs. 1 to 3.

Fig. 5 is a vertical sectional view, taken along the line 5—5 of Fig. 2.

Fig. 6 is a plan view of the gear unit for driving the ring turning gear, and also the bobbin respooling means.

Fig. 7 is a vertical sectional view, taken along the line 7—7 of Fig. 6.

Fig. 8 is a vertical sectional view, taken along the line 8-8 of Fig. 6.

Fig. 9 is a vertical sectional view, taken along the line 9-9 of Fig. 7.

5 Fig. 10 is a front elevation of the winding shuttle driving means, and the automatic throw out clutch.

Fig. 11 is a vertical sectional view taken along the line 11-11 of Fig. 10.

10 Fig. 12 is a plan view of the shuttle driving means and throw-out clutch.

Fig. 13 is a horizontal sectional view, taken along the line 13-13 of Fig. 10.

15 Fig. 14 is a side elevation showing the ring supporting and clamping means detached from the machine, these parts being the smallest diameter ring to be wound, and the ring being shown in place.

20 Fig. 15 is a plan view of the parts shown in Fig. 14, partially broken away, the ring being removed.

Figs. 16 and 17 are views similar to Figs. 14 and 15, and showing a larger diameter ring, and the supporting and clamping means therefor.

25 Figs. 18 and 19 are views similar to Figs. 14 and 15, and showing a still larger size ring, and the supporting and clamping pitch therefor.

Fig. 20 is a perspective view showing a wound rheostat ring as wound by the machine.

30 Fig. 21 is an enlarged plan view of the automatic latching means employed.

Similar reference characters indicate corresponding parts throughout the several figures of the drawings.

35 Referring to the drawings, and particularly to Figs. 1 to 3 thereof, the machine, according to the exemplary illustrated embodiment of the invention, is mounted upon a stand comprising angle iron legs 10, and a rectangular top 11 formed of angle iron, welded or otherwise secured to the legs, and upon this stand there is supported the base of the machine consisting of a rectangular plate portion 12 and a rectangular plate portion 13, the latter being in a higher plane than the portion 12 and provided at its ends with vertical leg portions 14 and 15, the leg portion 14 being secured to the inner ends of the plate portions 12 and 13, as by welding or the like, and the leg portion 15 being secured to the outer end of the plate portion 13. Triangular shaped brace portions 16 and 17 are provided between the leg portions 15 and 16 and the under side of the plate portion 13, the brace portion 16 being flush with the forward edges of the leg portion 14 and plate portion 13, for the purpose of mounting a part of the machine as will hereinafter more fully appear, and the brace portion 17 being preferably centrally disposed between the front and rear edges of the leg portion 15 and the plate portion 13.

40 Upon the left hand end of the plate 12 there is mounted a variable power unit 18 having its end flanges 19 secured by bolts 20, which bolts extend downwardly through the plate portion 12 and the top of the supporting frame 11 and are secured by nuts 21, these bolts thereby securing both the plate portion 22 and the variable power unit in place. Upon the leg 15 there are welded angle brackets 22 which are secured to the top frame portion 11 by bolts 23 extended downwardly through the top of said frame portion and secured by nuts 24.

45 The parts of the variable speed driving means of the machine are mounted upon the plate 12, while the parts for supporting and rotating the

ring to be wound, and the shuttle for winding the wire thereon, are mounted upon the base portion 13.

50 For the sake of clarity the ring supporting and shuttle mechanism mounted upon the plate 13 will be first described.

Substantially centrally of the base 13 there is secured by means of bolts 25 a post 26 of generally cylindrical shape having a cylindrical vertically extending opening 27 therein, and provided at its upper end with an outwardly extending flange 28. A slot opening 29 extending toward the rear of the machine is provided in the post 26 and its top flange 28, within which the winding shuttle is adapted to operate and be movable, as will hereinafter more fully appear, and a segment of the post 26 is cut out as at 30, the horizontal top wall of this cut-out being shown in Fig. 5 in spaced relation to the base 13, and the vertical front wall being shown in Fig. 2 at a right angle to one wall of the slot 29, the cut-out extending to this slot and providing a space within which the slidably adjustable carrier of the winding shuttle is engaged, as will hereinafter more fully appear.

55 In surrounding relation to the top flange 28 of the post 26 there is provided a cover plate 31 of ring shape, having a slot 32 disposed at the rear in alignment with the slot 29 of the post 26, the inner periphery of the plate 31 being spaced from the outer periphery of the flange 28 thereby providing a circular slot 33.

60 The plate 31 is mounted upon a segmental circumferential wall 34 extending from one wall of the slot 32 to a point in spaced relation to the forward central point of the plate 31, upon a segmental wall portion 35 extending from the other wall of the slot 32 to one of the pair of spaced guide gibs 36-36 secured upon the base 13 by means of screws 37, and which guide gibs 40 are parallel to the slots 29 and 32 and are adapted to support and guide the shuttle carrier as will hereinafter more fully appear, and upon a segmental wall portion 38 extending from the forward line of the gibs 36-36 to a point spaced 45 from the forward central point of the plate 31, the segmental wall portions 34, 35 and 38 being secured to the base 13 by means of bolts 39, which bolts also secure the cover plate in place.

65 A ring gear supporting bearing wall comprises 50 two segmental sections arranged within the wall portions 34, 35 and 38, one segmental section 40 extending from the right hand side of the slot 32 to the forward line of the gib members 36-36, and the other segmental section 41 extending 55 from the left hand side of the slot 32 to the side edge of the right hand gib member 36 and in flush relation to the end of the wall portion 35. The wall sections 40 and 41 are secured to the base 13 by means of suitably spaced screws 42.

70 The wall sections 40 and 41 are provided at their inner peripheries with upwardly projecting flanges 43 and 44, respectively, forming an annular bearing for the inner periphery of a worm ring gear 45 mounted upon the wall portions 40 and 41, this ring gear being supported upon a series of radially disposed antifriction rollers 46 disposed in pockets 46 in said wall portions and secured against longitudinal displacement by set screws 47 engaged upwardly in the wall portions 70 40 and 41, and having studs 48 at their upper ends engaging annular grooves 49 in the rollers.

75 The ring gear 45 is provided at one point with a projecting pin 50 which operates an automatic mechanism for stopping the machine at a pre-

determined point, as will hereinafter more fully appear, and the wall members 34, 35 and 28 are provided in their inner peripheral surfaces with slots 51 through which this pin moves. The shank of the pin 50 is threaded and may be selectively engaged in one or the other of three threaded holes 50^a, 50^b and 50^c provided in the ring to vary the point at which it actuates the stopping mechanism. Its degree of projection may also be varied by screwing it in or out to secure fine adjustment of its actuation point, as will hereinafter more fully appear.

A radially disposed arm 52 is secured to the ring gear 45 by means of screws 53, the inner end of this arm extending beneath the slot 33 where it is provided with a square hole 54 for interlocking engagement therewith of the clamping means of the ring to be wound, it being understood that as the ring gear is rotated the clamping means is rotated and rotates the ring, the ring being rotatably supported upon the post 26, and which ring supporting and clamping means will be presently more fully described.

The plate 31 is provided at its forward central portion with a rectangular cut-out 55 and the base plate 13 is provided with a pair of parallel T-slots 56—56, and within which cut-out and slots the driving worm for the ring gear and its supporting bearing is mounted. A slide member 57 having a pair of spaced bearing standards 58—58 at its upper side is provided at its lower side with a pair of T-bars 59—59 engaging the T-slots 56—56 of the base 13, the bearing standards and the bars being secured to the slide member 57 by screws 60. A worm 61 disposed between the bearing standards 58—58 has its shaft 62 journaled in said standards, one end of this shaft having secured thereon one member 63 of a universal joint drive connection, the other member 64 of which has a shaft 65 slidably connected thereto at one end by a spline 66, its other end being connected, as will hereinafter be more fully described, by a universal joint connection, to a variable speed driving gear unit. The worm gear support 40 is provided at its front central portion with a cut-out 67 in which the inner end of the worm supporting slide 57 engages in the inwardly moved operative position of the worm 61.

The slide 57 is adapted to move inwardly and outwardly to respectively engage and disengage the worm with respect to the worm ring gear 45, and for this purpose the T-bars 59—59 are provided at their under sides with posts 70 and 71, respectively, to which springs 72 and 73 are connected at one end, the other ends of these springs being connected to a post 74 secured to the underside of the base plate 13 between the T-slots 56—56, and which springs normally tend to pull the slide 57 and the worm gear carried thereon out of engagement with the worm ring gear 45.

For the purpose of engaging the worm with the worm ring gear a cam lever 75 is pivotally mounted by a shouldered cap screw 76 upon the base 13 between the T-slots 56—56, and which upon being pulled outwardly from the position shown in Fig. 2 will have its cam surface 77 engaged with a bearing portion 78 upon the slide plate 51, and will force the slide plate inwardly, meshing the worm 61 with the worm ring gear 45, in which position the slide and worm are retained by means of an automatic latching mechanism, the cam lever 75 being returned, upon release, to its normal disengaged position by means of a spring 79.

The automatic latching means consists of a supporting block 80 secured by screws 81 to the base plate 13 and provided in its upper side with a T-slot 82 in which there is slidably engaged a locking bolt 83, the nose end of which is adapted to engage a locking recess 84 in the bearing standard 58, the bolt being normally pressed in projecting direction by means of a spring 85 connected between a pin 86 secured to the under side of the cover plate 31 and one end of a lever 87 pivotally secured at 88 upon the upper side of the block 80, the other end of this lever having a slot 89 therein which engages a pin 90 provided upon the outer end of the bolt 83, and through which connection the spring exerts projecting pressure upon the bolt, so that when the recess 84 comes into register with the bolt as the slide 57 is moved inwardly the bolt automatically engages the recess and locks the worm in position. The lever 87 has secured upon one edge a bar 91 which projects outwardly to provide a handle for manually disengaging the bolt when desired. The inner end of the lever 87 has an inclined face 87^a disposed in the path of the pin 50 carried by the worm gear, so that by adjusting the degree of projection of the pin the point where it engages the face 87^a may be varied to thereby secure fine accuracy in the stopping point.

It will be understood that when the bolt is disengaged from the recess 84 the worm 61 will be withdrawn from engagement with the worm ring gear 45 through the outward pull of the springs 72 and 73, and such disengagement occurs automatically when the ring gear is rotated in clockwise direction to a point where the pin 50 engages the face 87^a and through the swinging of the lever 87 withdraws the locking bolt, this action occurring at a predetermined point determined by the ending of the winding operation. The bolt may also be manually withdrawn when desired by means of the handle end of the bar 91.

As before pointed out the machine is primarily intended for the winding of wire or the like about a solid continuous core, and especially the winding of wire about the ceramic ring or core of a rheostat, such ring or core A and wire winding B being shown in Fig. 20. This ring is rotatably supported upon the post 26 and is clampingly connected to the worm ring gear 45 so that as the ring gear is rotated the ring A will be rotated with it. The support for the ring A consists, as shown in Figs. 4, 5, 14 and 15, of a circular plate 92, having a slot 93 adapted to register with the slot 29 of the post 26, provided with an outwardly projecting peripheral flange 94 spaced from the upper surface of the post 26, and provided adjacent its inner periphery with a platform portion 95 having a series of radially disposed bearing recesses 96 in which anti-friction rollers 97 are engaged and secured against longitudinal movement by means of set screws 98 engaged in annular recesses 99 of the rollers. These rollers project above the surface of the platform portion 95 to support the ring A, and upon the inner ends of the rollers there are provided conical rollers 100 which engage the lower beveled surface of the inner periphery of the ring A, to thus maintain the ring against lateral displacement and centralize it.

The upper surface of the support 92 is provided with an annular recess 101 in which a guide roller of the clamping means moves, as will presently more fully appear. The support 92 is adapted

to be removably secured to the post 26 by means of screws 102, it being understood that when larger diameter rings are being wound a larger support will be mounted upon the post 26.

5 The ring clamping means consists of a block 103, the inner end of which is provided at its lower portion with a recessed face 104 adapted to fit about the periphery of the plate 92 and its flange 94, this recessed portion having a guide 105 rotatably secured at its under side by means of a screw 106 and which roller is adapted to move in the annular recess 101.

10 The upper portion of the inner face of the block 103 is adapted to engage the flat mounting

15 surface *a* of the ring A, said block being provided at each side with outwardly projecting apertured flanges 107—107 through which are slidably engaged horizontally movable clamping pins 108—108, the forward ends of which are adapted 20 to be projected into engagement with recesses *b—b* provided in the flat surface *a* of the ring A, the outer ends of these pins being secured to the ends of a cross bar 109 slidably engaged in a slot 110 extending transversely through the block 103.

25 A handle 111 is secured centrally of the bar 109 and extends upwardly through a slot 112 in the upper surface of the block 103, and by means of which the bar 109 may be manually moved back and forth to disengage and engage the pins 108

30 with the ring A.

In order to insure uniform movement of each of the pins 108, the bar 109 is provided at its ends with a rearwardly projecting extensions 114—114 engaging the side surfaces of the block 103 35 rearwardly of the slot 110, so that the bar is always in properly aligned position as it is moved back and forth in the slot 110.

In addition to the clamping provided by the pins 108 the ring is also clamped at the top and 40 for this purpose there is provided a clamping plate 115 removably secured to the upper side of the block 103 by a screw 116, having an inwardly projecting portion 117, adapted to engage the upwardly projecting portion *c* formed 45 upon the ring A, and provided with vertically disposed downwardly projecting pins 118—118, adapted to engage vertically disposed holes *d* provided in the portion *c* of the ring A. The plate 115 is provided at its rearward end with 50 an open ended slot 119 in which the handle 111 is engaged, such engagement preventing relative rotary movement of the plate.

It will be understood that in securing the ring in place the pins 108 are first engaged with the holes *b* whereupon the cap 115 is screwed down to engage the pins 118 with the holes *d*.

The plate 115 is provided at each side with a downwardly projecting flange 120 engaging the side surface of the block 103 above the ends of 55 the bar 109 to insure alignment of the cap with the block. In order to automatically disengage the cap from the ring, when released by unscrewing of the screw 116, springs 121—121 are disposed in pockets 122—122 provided in the upper 60 surface of the block 103 and exert upward pressure upon the under surface of the cap plate 115. These springs also hold the plate 115 against looseness when for any reason the pins 118 are not pressed downwardly into the holes *d* to the 70 full limit.

The block 103 is provided at its rearward end with a vertically disposed cylindrical passage 123 in which a post 124 is engaged, this post being provided at its lower end with a squared shank 125 which engages the square hole 54 of the arm

52, and having a cross pin 126 which seats in recesses 127—127 at the upper end of the passage 123. The post 124 is provided at its upper end with an outwardly extending handle 128, by means of which the clamping block, ring A, and gear 45 may be manually turned to any desired position, it being understood that the gear 45 is free to rotate in either direction when the worm 61 is disengaged therefrom.

In order to additionally hold the ring A during the winding operation, so that the ring will be held downwardly upon the rollers 97, there is provided hingedly mounted resilient holding means for engaging the upper annular beveled surface of the inner periphery of the ring. An upright standard 129 is mounted upon the rearward portion of the cover plate 31 and bridges the rearward end of the slot 32, the base portions 130 of the standard being secured to the cover plate by means of screws 131. Upon the upper end of the standard there are provided a pair of bearing flanges 132—132 between which an arm 133 is hingedly mounted by means of a shaft 134 extending through passages in said bearing portions and said arm, this shaft being removable for the purpose of substituting different sized arms, the purpose of which will hereinafter more fully appear, and the shaft being provided at one end with a knurled head 135 to permit its convenient insertion and removal.

The arm 133 is preferably bifurcated, and at the forward end of each side portion there is provided a vertical bearing passage 136 in which a shaft 137 is mounted for vertical sliding movement, each of these shafts having a head 138 screwed upon its upper end to limit its downward movement and being provided upon its lower end with a bracket 139 upon which a conical roller 140 is rotatably mounted, and which roller is adapted to engage the upper beveled surface of the inner periphery of the ring A. A spring 141 is disposed between the bracket 139 and the arm 133 and normally presses the roller downwardly into engagement with the ring. The arrangement of the roller is such that it will yield upwardly to compensate for direct engagement with the surface of the ring A and also for engagement with the surface of the wire B when the latter is wound about the ring, and the shaft 137 may also rotate so that the roller is maintained in proper engagement with the ring surface.

In order to secure the arm 133 in operative position there is secured upon one side of the standard 129 by means of screws 142 a triangular shaped plate 143 upon the forward end of which there is mounted a locking pin 144 slidably engaged in a passage 145 and supported in a bracket 146 secured upon said arm, a spring 147 being provided upon the pin between said bracket and a collar 148 secured upon the pin and which normally presses the pin inwardly to engage a pocket 149 provided in the side of the arm 133. Upon disengagement of this pin from the arm, the arm may be swung rearwardly to an inoperative position, where it will rest upon a supporting block 150 secured upon the rearward surface of the standard 129, the upper end of this block 150 being beveled so that the arm will be supported at an upwardly inclined angle, as shown in Fig. 2.

Slidably mounted between the gibbs 38—38 there is provided the supporting block member 151 upon which the wire winding shuttle and driving means therefor is mounted, this block having a dovetail portion 152 at its lower portion

which engages between the gibs and being provided in its upper surface with a recess 153 through which the worm ring gear 45 moves. The vertical wall of this recess has a slot 154 therein through which the pin 50 of the ring gear moves. The upper surface of the block 151 projects beyond the left hand edge of the cover plate 31 as shown in Figs. 2 and 5, this left hand edge of the cover plate being provided with a straight surface 155 disposed parallel to the gibs 36-36, and the block has mounted upon its upper surface a bar 156, secured to the block member 151 by means of screws 157, and which slidably abuts the surface 155.

15 Integrally formed upon the block 151 there is provided an extension block portion 158, the rearward edge of which is flush with the rearward edge of the block portion 151, while the forward edge is rearwardly spaced from the forward edge of the portion 151, and extends into the recess 30 of the post 26 so that its forward face is within the bore 27 and within the slot 29 of the post 26.

Upon this forward face of the portion 158 a vertically disposed shuttle mounting plate 159 is secured by screws 160 this plate extending upwardly above the ring supporting plate 92, its upper portion having a circular outline and being provided with a circular opening 161 from which 25 a radial opening or slot 162 extends in upwardly and forwardly inclined relation to the outer periphery of the plate 159. The opening 161 is provided adjacent the rearward surface of the plate 159 with an annular recess 163, the opening 161 and this recess 163 constituting a bearing 30 for the wire winding shuttle.

40 The winding shuttle consists of a gear 164 provided with a central opening 165 coaxial with the opening 161, having a radial opening or slot 166 extending from the opening 165 to the periphery of the gear, the opening 166 being provided with a rearwardly extending bearing flange 167 rotatably engaged in the opening 161 and having a segmental retaining ring 168 secured to its rearward surface and disposed within the annular recess 163.

45 The shuttle gear 164 is adapted to have the wire to be wound about the ring A mounted thereon, and during the winding operation is rotated. At one point in the rotation the slot 166 registers with the slot 162, thus providing the opening through which the ring A may be placed upon the supporting plate 92 in surrounding relation to the shuttle, and after the winding operation may be removed.

50 The driving means for the shuttle gear consists of a pair of spaced gears 169 and 170 rotatably mounted upon the plate 159 by means of bearing studs 171 and 172, these gears 169 and 170 having a pinion gear 173 meshed therewith, this pinion gear being keyed upon the projecting end of a shaft 174, which shaft extends through a passage 175 in the block portions 158 and 151, the forward end of the shaft being rotatably supported in a ball-bearing unit 176, disposed in a recess 177 formed in the forward face of the block portion 158, and the rearward end of the shaft being journaled in a bushing 178 disposed in a recess 179 formed in the rearward surface 70 of the block portion 151. The edge of the gear 169 engages in a slot 168 in the post 26.

Upon the outer end of the shaft 174 there is keyed one member 180 of a universal driving connection element, the other member 181 of which is keyed to the end of a drive shaft 182.

It will be seen that upon rotation of the gear 173 the gears 169 and 170 are rotated, and these in turn rotate the shuttle gear 164, the spacing of the meshing points of the gears 169 and 170 with the shuttle gear 164 being such in relation to the slot 166 that at least one of the gears 169 and 170 is at all times meshed with the teeth of the shuttle gear 164, so that the latter is continuously driven. While the gears 164, 169, 170 and 173 are shown as spur gears it will be understood 10 that spiral or other desired types of gears may be employed.

Upon the shuttle gear 164 there is provided a spool mounting post 183 upon which the spool 184 carrying the wire to be wound about the core 15 A is supported, this spool being removably mounted upon the post 183, and frictionally retained by means of a slotted leaf spring 185 slipped into engagement with an annular groove 186 provided in the end of the post, and which spring 20 frictionally retards the rotation of the spool as the wire is wound, so that there will be no slack in the wire. At a point adjacent one side of the slot 166 a grooved wire guide roller 187 is mounted upon a stud 188, and between the spool and the 25 guide roller there is provided a calibrated tension member 189 having its circular shank 190 rotatably disposed in a recess 191 in the shuttle gear and, adapted to be retained in adjusted position by means of set screws 192 and 193 engaged 30 with the edge of the member 189.

Two wire guide rollers 194 and 195 are rotatably mounted upon the tension member at diametrically opposed points at each side of the center. The wire B is adapted to extend from 35 the spool 184 through an apertured guide member 196 mounted upon the shuttle gear over the guide roller 194 and under the guide roller 195, and thence over the guide roller 187 from which it is connected to the ring A. By adjusting the 40 position of the calibrated tension dial the bends between the wire extending over the guide rollers may be increased or diminished and thus the tension may be accurately predetermined and maintained.

45 As seen in Fig. 4 the shuttle is rotatable in clockwise direction during the winding operation, and as it rotates it winds the wire B about the core A, the latter being simultaneously rotated through rotation of the worm ring gear 45, so 50 that the wire is wound as a helix about the core with the convolutions in spaced relation to each other, it being understood that the end of the wire is secured to the ring at the beginning of the winding operation and upon completion of 55 the winding operation the wire is cut and the cut end then secured to the ring.

The driving means for the wire winding shuttle gear 164 and the core driving worm ring gear 45 will now be described, it being understood that 60 these driving means are respectively connected to the shaft 182 connected to the pinion gear 173 and to the shaft 162 of the worm 65 81.

The variable power unit 18, which is a standard type of unit provided with a pair of driving shafts 65 187 and 188, which are respectively connected by mechanisms presently to be described with the respective shafts 182 and 62, contains mechanism 70 which may be adjusted by turning the knob 199, and which adjustment is indicated by the hand 70 200 upon the dial 201, which causes any desired variation between the speeds of the shafts 187 and 188, these standard units being therefore known as infinite variation units. The use of this unit in the present combination structure makes 75

possible the rotation of the ring A and the winding of the wire B about it at any desired relative speeds, so that the pitch and spacing of the windings may be infinitely varied as desired, depending upon the particular sizes of the ring and wire and the requirements of the rheostat, or other article to be wound.

The shaft 197 connects with the main drive of the unit 18, being projected for this purpose from the rear wall of the unit and having splined thereon a clutch collar 202 having clutch teeth 203 and 204 at its opposed faces, and which are adapted upon shifting of the clutch collar to respectively engage clutch teeth 205 and 206 provided upon the pulleys 207 and 208 rotatably mounted upon the shaft 197, these pulleys being of different diameters, and adapted to be driven by belts 209 and 210 extending about pulleys 211 provided upon the shaft of a driving motor 212, mounted upon the support 213 secured to the base form. The tension of the belts may be regulated by means of tension rollers 214—214, carried upon an arm 215, pivoted upon the frame 216, and adapted to be secured in adjusted position by means of a nut and bolt connection 217 engaging a slot 218 of an arm 219 pivotally secured at 220 to the frame.

The clutch collar 202 is adapted to be operated by means of a fork lever 221 having rollers 222 at its upper end engaged with the collar, the lever being pivotally mounted at 223 upon a bracket 224 and connected at its lower end by a link 225 to an eccentric throw 226, provided upon a shaft 227 mounted in suitable bearings upon the base 35 of the power unit and provided at its forward end with a hand wheel 228, rotation of this hand wheel in one or the other directions adapted to engage the clutch with one or the other pulleys 207 and 208, so that either speed desired may be 40 used to drive the power unit.

The drive shaft 197 is connected to the shaft 182 by clutch mechanism adapted to be automatically engaged and disengaged, the automatic engagement and disengagement respectively taking place simultaneously with the manual engagement of the driving worm 61 with the ring gear 45, and its automatic disengagement therefrom through tripping of the latch bolt 83 by means of pin 50 upon completion of a winding operation, as previously pointed out.

The shaft 182, which is splined at one end to the universal joint connection member 181, is keyed at its other end to one member 229 of a universal joint driving connection, the other member 230 of which is keyed to a shaft 231 journaled in a bearing standard 232 mounted upon the base plate 12, this shaft having the hand wheel 233 and a clutch member 234 secured thereon, this clutch member having clutch teeth 235 at one end, and being of tubular form to provide an interior pocket, which will presently be more fully referred to.

In axial alignment with the shaft 231 and in spaced relation thereto there is secured in the bored end of the shaft 197 a driving shaft 236 upon which a clutch collar 237 is slidably connected by means of a spline 238, this clutch collar having clutch teeth 239 at one end opposed to the clutch teeth 235, and having a bore 240 which forms with the bore of the clutch member 234 a pocket in which is disposed a helical spring 241 which normally exerts pressure to separate the clutch teeth from each other.

The clutch collar 234 is provided with an annular groove 242 engaged by rollers 243-243.

mounted in the yoke portion 244 of a clutch engaging and automatic throw out lever 245 which is pivotally mounted at its lower end by means of a shouldered cap screw 246 upon a block portion 247 secured upon the base plate 12. Upon the block 247 a locking pawl 248 is pivotally mounted by means of a shouldered cap screw 249 and is provided at one end with a tapered locking tooth 250 adapted in the locked position to engage a tapered hole 251 provided in the lever 245, being held in engagement with this tapered hole by means of a spring 252 tied between a pin 253 provided upon the locking pin and a pin 254 provided upon the block 247. 5 10

The locking pawl is in the form of a bell-¹⁵ crank lever, and at its outer end is pivotally connected by means of a shouldered cap screw 255 to one end of a rod 256, which extends through a slot 257 in the vertical wall portion 14 of the base, see Figures 4 and 8, and is pivotally connected at its upwardly offset other end 258 to the sliding support of the worm 61, this connection being preferably made by means of the pin 20 70 to which one end of the spring 72 is connected.

It will thus be seen that the shuttle driving clutch which is shown engaged in Figs. 10 to 13 will be automatically engaged upon manual engagement of the worm 61 with the gear 45 through the camming engagement of the tooth 250 with the slot 251, and will be automatically disengaged upon either manual or automatic disengagement of the worm 61 from the worm ring gear 45, the forward movement of the worm support as the worm is disengaged pulling the rod 256 and causing the locking pawl 248 to turn and disengage its locking tooth 250 from the lever 245, whereupon the spring 241 presses the clutch collar 237 to the left, as seen in Figs. 10 and 12, and disengages the clutch teeth 239 from the clutch teeth 235, thereby stopping the wire winding shuttle simultaneously with the stopping of the rotation of the ring A.

Between the drive shaft 198 of the variable power unit and the shaft 68 for driving the worm 61 the changeable gear means is provided for imparting power from the shaft 198 to the shaft 65, such gear means also being arranged to drive respooling mechanism mounted in relation thereto. The shaft 198 has keyed in its bored end one end of a shaft 259, the other end of which is journaled in a bearing standard 260 mounted upon the left hand edge of the base plate 13, a collar 261 being keyed upon the projecting end of the shaft adjacent the bearing standard. At an intermediate point the shaft 259 is journaled in a bearing standard 262 mounted upon the base plate 12, and between the standards 262 and 260 there are keyed upon the shaft 259 a bevel gear 263 and a spur gear 264, a spacing collar 265 being disposed between the spur gear 244 and the bearing standard 260.

The bevel gear 263 meshes with a bevel gear 266 keyed upon the end of an inclined shaft 261, journaled in spaced bearing portions 268 and 269 of a bearing standard 270 mounted upon the base plate 12, a worm 271 being secured upon the shaft 267 between the bearing portions 268 and 269, and a retaining collar 272 being secured upon the lower projected end of the shaft.

The worm 271 meshes with a worm gear 273 **70** loosely mounted upon a shaft 274, and adapted to be connected thereto to drive it by slidable key means presently to be more fully described, the shaft being journaled at one end in a bearing standard 275 mounted upon the base plate 12 and **75**

at its other end in a bearing standard 276 mounted upon the left hand edge of the base plate 13, this end of the shaft having a projecting reduced diameter extremity 277, to which is keyed one member 278 of a universal joint driving connection, the other member 279 of which is slidably splined to the shaft 65.

The spur gear 264 meshes with a spur gear 280 also loosely mounted upon the shaft 264 and adapted to be connected thereto to drive it by means of the sliding key, presently to be more fully described, this spur gear 280 having rigidly connected to it a spur gear 281 secured by pins 282, and the spur gear 281 having rigidly connected to it a smaller diameter spur gear 283 secured by pins 284, the gears 280, 281 and 283 adapted to rotate as a unit and the gears 281 and 283 adapted, as will hereinafter more fully appear, to drive the respooling mechanism. A spacing collar 285 is disposed upon the shaft 274 between the worm gear 273 and the bearing standard 275. The portion of the shaft 274 extending from within the spur gear 280 to the end of the shaft journaled in the bearing standard 275 is provided with a cylindrical bore 286 and there is a longitudinal slot 287 in the shaft extending the length of the bore and communicating with it.

A slide rod 288 is engaged in the bore 286 and has a projected key 289 secured in its end, which key engages the slot 287 and projects into engagement with a slot 290 in the hub of the gear 280, in one position, and in a slot 291 in the hub of the worm gear 273, in another position, it being understood that in these respective positions the spur gear 280 and the worm gear 273 are individually keyed to the shaft 274 to drive it, the other gear running idle.

The rod 288 projects through a passage 292 provided in a plate 293 secured by screws 294 to the bearing standard 275 and it is provided upon its end with a hand wheel 295. A pair of spaced annular grooves 296 and 297 are provided in the rod 288, and one or the other of these grooves, depending upon the position of adjustment of the key 289, is engaged by a pair of yieldable retaining balls 298—298 disposed in passages 299—299 in the plate 293 and pressed toward the rod 288 by means of springs 300—300, and thus releasably retain the rod in one or the other of its operative positions. As will be clear from Fig. 7 the key is in engagement with the gear 280 when the rod 288 is in position to have the groove 296 engaged by the balls 299—299, and when the rod 288 is pulled out to engage the balls with the groove 297 the key is in engagement with the worm gear 273. By this arrangement the worm 61 for driving the ring 45 may be selectively driven, either by the worm gear 273 or the spur gear 280.

Upon the base plate 12, forwardly of the shaft 274 and the gears carried thereby, there is secured a bearing standard 301, in which is journaled a spool winding shaft 302, this shaft having secured thereon a small diameter spur gear 303 in alignment with the large diameter spur gear 281 and a large diameter spur gear 304 in alignment with the small diameter spur gear 283, the end of the shaft projecting beyond the hub of the gear 304 and being secured to the spindle 305 of an automatic counting device 306 mounted upon the base plate 13, the counting device being for the purpose of keeping record of the number of turns of wire wound upon the spool.

The spool winding shaft 302 is adapted to be driven either by the gear 281 or the gear 283,

and for this purpose a pair of clutch arms 307 and 308 are pivotally mounted upon stud shafts 309 and 310 projecting at each side of a bearing standard 311 mounted upon the base 12. The arm 307 has a spur gear 312 mounted thereon by means of a shouldered cap screw 313 and is adapted to mesh with the spur gears 281 and 303 in its operative position, as shown in Fig. 8, while the arm 308 has a spur gear 314 mounted thereon by means of a shouldered cap screw 315, and is adapted in the operative position of the arm to mesh with the spur gears 283 and 304, it being understood that only one of the arms is in operative position at one time. As shown in Fig. 8 the arm 307 is in operative position and the arm 15 308 is in inoperative position, the latter being dropped into engagement with the base plate 12 in this inoperative position and being raised from the base plate in the operative position.

Handles 316 and 317 are respectively provided upon the forward ends of the arms 307 and 308, to facilitate operating them and the arms are respectively provided near their forward ends with holes 318 and 319, with which a slidable locking bar 320, mounted in a block 321 secured to the bracket portion 16 of the base 12 is adapted to engage, this rod clearing the upper surface of the lowered arm 308 when it is engaged with the hole 318 of the arm 307. The locking rod 320 is adapted to be secured in locked position by a set screw 322 provided in the block 321. It will be understood that, depending upon which of the arms 307 and 308 is in operative position, the spool winding shaft will be driven by either one or the other of the gears 281 and 283.

Upon the left hand end of the shaft 302 there is provided a spindle 323 upon which the spool 184 is engaged and retained by a collar 324, it being understood that this spool can be respoled with wire while a similar spool 184 is in operation upon the shuttle 164, so that the respooling operation may be carried on simultaneously with the winding of the ring A.

Upon the forward surface of the bearing standard 301 there is provided an angle bracket 325, which is hingedly mounted at its lower end by means of a hinge pin 326 having bearing in projecting bearing portions 327—327 formed upon the lower end of the bearing standard 301, this bracket adapted to be secured in raised operative position by means of a screw 328, engaged in the bearing standard 321 and extended through a vertical slot 329 in the vertical portion of the bracket, a wing-head 330 being provided at the outer end of the screw which is adapted to pass freely through the slot in its vertical position and to lockingly engage the surface of the bracket in its horizontal position, so that by moving the screw to bring its head into the vertical position the bracket may, when not in use, be swung 60 downwardly out of the way.

Mounted upon the bracket 325 is a block 332 having a T-slot 333 therein in which is slidably engaged a T-bar 334, upon the end of which is rotatably mounted a wire guide roller 335, this roller being secured upon a removable pin 336 set in the end of a socket in the end of the bar 334 and secured by a set screw 337, the roller being retained upon the pin by a headed screw 338. The bar 334 is provided with a handle 339 intermediate the ends of its upper surface, and at its rearward end is provided with a stop plate 340 to limit the sliding movement of the bar, it being understood that the bar may be slid back and forth for the purpose of positioning the guide 75

roller 333 with respect to the particular spool being wound, these spools on occasion being of different width.

- 5 A supply of wire is carried upon a large flanged spool 341 removably supported upon the frame 11 by means of depending supports 342 and 343, the support 343 having an inwardly projecting pin 344 mounted in its lower end for engagement with one end of the central bore 345 of the spool, 10 and the support 343 being provided at its lower end with a retractable spring pressed pin 346 having a spring 347 mounted thereon between the support 343 and a collar 348, the end of the pin adapted to engage the other end of the bore 345 of the spool. A knurled head 349 is provided upon the end of the retractable pin 346 for the purpose of disengaging the pin from the spool to permit removal of the spool and mounting of a new spool in its place.
- 15 20 As shown in Figs. 1 to 5, and Figs. 14 and 15, the machine is arranged to wind wire upon a ring of relatively small diameter. However the machine is adapted by adjustment and interchangeability of parts to the winding of a ring having a diameter substantially as large as the outside diameter of the flange 28 of the post 26, and also to wind rings of any diameter between the small diameter ring as illustrated in Fig. 14 and the large diameter ring as illustrated 25 in Fig. 18.
- 25 30 In Figs. 16 and 17 I have illustrated a replacement ring support 92^a substantially similar in construction to the ring support 92 but of larger diameter, this support being suitable for the support 35 port of rings of sizes of an intermediate range of diameters between the minimum and maximum limits of the machine. This support 92^a, like the support 92, has a radial slot 93^a, a flange 94^a, a platform support 95^a provided with radial roller 40 recesses 96^a and cylindrical rollers 97^a rotatably mounted therein and provided with conical rollers 100^a at their inner ends. An annular recess 101^a is provided for engagement of the roller 105^a of the ring clamping block 103^a, this block being provided 45 at its inner end with a recess 104^a for engaging about the periphery of the ring support, and being provided at its inner end above the ring support with outwardly projecting apertured flanges 107^a—107^a through which are slidably engaged horizontally movable clamping pins 108^a— 50 108^a, adapted to engage the horizontal holes *b* of the ring, the rearward ends of these pins being mounted in a cross bar 109^a movable in a slot 110^a of the block.
- 55 55 The clamping head 115^a is secured to the upper side of the block 103^a by a set screw 116^a. The clamping head 115^a and its details are similar to the clamping head 115, except for slight variations in the dimensions, so that a further detail 60 description of these parts is not deemed necessary. A vertically disposed downwardly projecting square shank 350 is secured to the block 103^a, this shank being in the same relative position with respect to the central vertical axis of the support 65 as the shank 125 of the clamping member 103, so that when the ring support 92^a is mounted in place upon the post 26 the shank 350 will engage the square hole 54 of the arm 52. A handle 351 is secured to the rearward side of the clamping member 103^a for manually rotating the ring 70 to any desired position.

In Figs. 18 and 19 I have illustrated a large size ring support 92^b provided with a radial slot 93^b, and a flange 94^b having radial recesses 96^b therein which are engaged by cylindrical rollers 97^b pro-

vided at their inner ends with conical rollers 100^b. The ring clamping member 103^b is provided with a recessed inner end 104^b for engaging about the periphery of the ring support, and is provided at its inner end above the ring support with outwardly projecting apertured flanges 107^b—107^b, through which are slidably engaged the horizontally movable pins 108^b—108^b for engaging the holes *b* of the ring, these pins being secured at their inner ends to a cross bar 109^b 10 slidable in a slot 110^b of the block 103^b. The clamping head 115^b is secured to the upper side of the block 103^b by a set screw 116^b, and except for slight variations in the dimensions is similar in detail to the clamping heads 115 and 115^a. The block 103^b is provided at its under side with a depending square shank 352, also disposed in the same relative position with respect to the central axis of the support 92^b as the shank 125 with respect to the axis of the central support 92, 20 and is adapted to engage the square hole 54 of the arm 52. A handle 353 is secured to the rearward side of the clamping member 103^b for manually rotating the ring to any desired position.

In the use of the ring supporting and clamping structures shown in Figs. 16 and 17, and 18 and 19, interchangeable replacement clamping arms 133 are mounted in place upon the support 129, these arms being relatively shorter than the clamping arm 133, as shown in Fig. 4, and having their 30 roller supporting shafts 137—137 spaced wider apart, so as properly to engage the particular ring being wound. As these replacement clamping arms 133 are of the same structure as the clamping arm 133, shown in Fig. 4, except for 35 length and width, their illustration in the drawings is not deemed necessary for the clear understanding of the invention.

In arranging the machine for winding different diameter wires it will be understood from the foregoing that the central vertical axis of the ring A being wound remains constant and is coincident to the central axis of the post 26, but that the position of the body of the ring varies with respect to the central vertical axis, so that the 45 wire winding shuttle must be shifted in order to bring its center into line with the center of the circumferential body of the ring. It is for this purpose that the block 151 is mounted for sliding movement in the gibbs 36—36. When the 50 supports 92^a and 92^b replace the support 92 the slide block 151, and the shuttle mechanism carried thereby, is simply moved rearwardly, being provided in its upper surface with three pockets 370, 371 and 372 in one of which a locking pin 373, 55 disposed in a hole 374 in the cover plate 31, is engaged to fix the position of adjustment of the slide block 151. The universal joint connections between the shaft 174 and the shaft 231, as well as the extensibility of the connection provided by 60 the splined slidable connection of the shaft 182 with the universal joint member 181, permits the sliding adjustment of the slide block 151 without disturbing the driving relation. The same is true of the driving connection between the slidable 65 support for the worm 61 and the shaft 274.

The operation of the machine is as follows:

The spool or bobbin 181, containing the wire suitable for the particular type of ring to be wound, is placed upon the shuttle gear 164, the 70 spool having previously been wound by the spooling mechanism. The shuttle is rotated by means of the hand wheel 233 to a point where the slot 166 registers with the slot 162 of the support 159, and the ring A, and to which one end of the

wire B, which has previously been carried about the tension and guide rollers, has been secured at one end by threading it into a suitable hole e provided in the ring for this purpose, is placed upon the ring supporting member 92 by inserting it through the slots 166 and 162 so that the ring surrounds the shuttle.

The ring is then clamped to the ring holding clamping block 103 by the clamping pins 108 and 118, and the holding arm 133 is swung into operative position, where it is locked by the locking pin 144 with the rollers 140 in engagement with the upper beveled surface of the inner periphery of the ring. The first turn of wire is wound by means of the hand wheel 233, the pitch of the winding being set to the calibrated dial 201 and locked, as well as by connecting either the spur gear 280 or the worm 273 to the shaft 274 by shifting of the key rod 288 by means of the handle 295. Also the desired tension for the particular wire is predetermined by adjustment of the calibrated tension dial 189. The particular speed is also predetermined prior to starting the machine, by engaging the clutch 202 with one or the other of the pulleys 207 and 208, it being understood that these preliminary adjustments are determined by the particular type of ring being wound and characteristics of the wire, a small gauge easily bendable wire being wound at a different speed from a heavy relatively stiff wire.

The machine is then started by engaging the worm 61 with the worm ring gear 45 by means of the hand lever 75, the shuttle driving clutch collar 237 being simultaneously engaged by means of the tie-rod 256 which upon inward movement of the worm support is pushed to rotate the bell crank pawl lever 248 in clockwise direction, causing the tapered pawl tooth 250 to enter the slot 251 of the clutch operating lever and through the camming action between the tooth and the slot swinging the lever to clutch engaging position.

The shuttle now rotates about the rotating ring winding the wire thereon, and this continues until the winding is completed. At the predetermined winding completion point the pin 50 engages the arm 91 tripping the lever 87 and disengaging the locking bolt 83 from the recess 84, whereupon the released worm gear support is drawn outwardly by means of the springs 72 and 73. Simultaneously therewith the shuttle driving clutch is released through the action of the tie-rod 256, the pull imparted thereto through the movement of the worm support rotating the bell-crank pawl lever 248 in clockwise direction and disengaging its tooth 250 from the slot 251, whereupon the spring 241 forces the clutch collar 237 and its teeth 239 out of engagement with the clutch member 241 and its teeth 235.

The wire is then cut between the ring and the spool, and the wound ring removed through the registering slots 166 and 162, the holding arm 133 having first been released and swung to its inoperative position upon the support 150. The operator then pulls the clamping unit back to the starting place by means of the handle 128, which action of course rotates the worm ring gear 45 back to the starting place.

It will be understood that at any time during the operation of the machine it may be stopped simply by tripping the locking pawl 84 by means of the lever 91. Also it is possible during the operation of the machine to vary the relative speed between the shuttle and ring, and consequently the pitch of the winding, by adjustment

of the power unit, such adjustment being shown on the dial 201.

In winding larger diameter rings than that shown in Figs. 1 to 15 the ring support 92 and the clamping block 103 are replaced by the ring support 92^a and clamping block 103^a, as shown in Figs. 15 and 17, or by the ring support ring 92^b and the clamping block 103^b as shown in Figs. 18 and 19, and the shuttle is shifted to bring its center into line with the circumferential center 10 of the ring to be wound, the shifttable shuttle support being secured in its shifted position by engagement of the locking pin 373 with one or the other of the pockets 371 and 372.

I have illustrated and described a preferred 15 and satisfactory embodiment of the invention, but it will be obvious that changes may be made therein, within the spirit and scope thereof as defined in the appended claims.

Having thus described my invention, what I 20 claim and desire to secure by Letters Patent is:

1. In a winding machine of the character described, a ring support for rotatably supporting a ring to be wound, means for rotating said ring on said ring support, a winding shuttle mounted 25 in relation to said support comprising an apertured annular member arranged to surround a portion of said ring and having a slot through which said ring may be engaged with said ring support, a rotatable spool removably mounted 30 upon said shuttle for containing material to be wound about said ring, a guide roller mounted upon said shuttle, tension means disposed between said spool and said guide roller comprising a rotatable member mounted upon said 35 shuttle and rotary adjustment about a central axis and a pair of spaced rollers carried by said member in non-coaxial relation therewith and means for securing the adjusted position of said member, adjustment of said member adapted 40 to change the angular relation of said spaced rollers with respect to said spool and guide roller, said material adapted to extend from said spool over and under said spaced rollers and over said guide rollers to the ring, and means for rotating 45 said shuttle.

2. In a winding machine of the character described, a fixed ring support for rotatably supporting a ring to be wound, said ring support having a central opening and a radial slot extending outwardly from said opening, a plurality of spaced anti-friction ring supporting rollers mounted radially in said ring support for supporting said ring substantially throughout its circumference, circumferentially arranged means 50 carried by said rollers adapted to engage the ring peripherally to center and retain it in coaxial relation with said support, for rotating said ring on said ring support, a winding shuttle mounted in said opening and slot of said ring 55 support comprising an apertured annular member arranged to surround a portion of said ring and having a slot through which said ring may be engaged with said support, means carried by said shuttle for containing material to be wound 60 about said ring, and means for rotating said shuttle.

3. In a winding machine of the character described, a fixed support for rotatably supporting a ring to be wound, said ring support having a 70 central opening and a radial slot extending outwardly from said opening, yieldable holding means arranged to engage said ring in opposed relation to said ring support, a winding shuttle mounted in said opening and slot of said ring 75

- support comprising an apertured member arranged to surround a portion of said ring and having a slot through which said ring may be engaged with said ring support, means carried by said shuttle for containing material to be wound about said ring, and means for rotating said shuttle.
4. In a winding machine of the character described, a fixed support for rotatably supporting a ring to be wound, said ring support having a central opening and a radial slot extending outwardly from said opening, yieldable holding means having rollers arranged to engage said ring in opposed relation to said ring support, a winding shuttle mounted in said opening and slot of said ring support comprising an apertured member arranged to surround a portion of said ring and having a slot through which said ring may be engaged with said ring support, means carried by said shuttle for containing material to be wound about said ring, and means for rotating said shuttle.
5. In a winding machine of the character described, a fixed ring support for rotatably supporting a ring to be wound, said ring support having a central opening and a radial slot extending outwardly from said opening, anti-friction ring supporting rollers mounted in said ring support, yieldable holding means arranged to engage said ring in opposed relation to said ring support, a winding shuttle mounted in said opening and slot of said ring support comprising an apertured member arranged to surround a portion of said ring and having a slot through which said ring may be engaged with said ring support, means carried by said shuttle for containing material to be wound about said ring, and means for rotating said shuttle.
6. In a winding machine of the character described, a ring support for rotatably supporting a ring to be wound, said ring support having a central opening and a radial slot extending outwardly from said opening, a ring mounting member removably secured to said ring support having an opening and slot respectively coaxial and aligned with said opening and slot of said ring support, means for rotating said ring on said ring mounting member, a winding shuttle mounted in said opening and slot of said ring support comprising an apertured annular member arranged to surround a portion of said ring and having a slot through which said ring may be engaged with said ring support, means carried by said shuttle for containing material to be wound about said ring, and means for rotating said shuttle.
7. In a winding machine of the character described, a ring support for rotatably supporting a ring to be wound, said ring support having a central opening and a radial slot extending outwardly from said opening, means for rotating said ring on said ring support, a winding shuttle mounted in said opening and slot of said ring support comprising an apertured annular member arranged to surround a portion of said ring and having a slot through which said ring may be engaged with said ring support, means carried by said shuttle for containing material to be wound about said ring, and means for rotating said shuttle, a ring mounting member adapted to be removably secured to said ring support and having an opening and slot respectively coaxial and aligned with said opening and slot of said ring support.
8. In a winding machine of the character described, a base, a ring support mounted upon said base for rotatably supporting the ring to be wound, a rotatable winding shuttle mounted in relation to said support adapted to wind material carried thereon about said ring, a ring gear mounted upon said base, means carried by said ring gear adapted to rotate said ring; a driving gear for rotating said ring gear, means movably mounted upon said base supporting said driving gear and movable to engage and disengage said driving gear with respect to said ring gear, releasable locking means adapted to retain said driving gear in engaged relation with said ring gear, means carried by said ring gear adapted at one point in its rotation to engage said releasable locking means to disengage it from relation with said driving gear, and means adapted to move said driving gear out of engagement with said ring gear upon release.
9. In a winding machine of the character described, a base, a ring support mounted upon said base for rotatably supporting the ring to be wound, a rotatable winding shuttle mounted in relation to said support adapted to wind material carried thereon about said ring, a ring gear mounted upon said base, means carried by said ring gear adapted to rotate said ring; a driving gear for rotating said ring gear, means movably mounted upon said base supporting said driving gear and movable to engage and disengage said driving gear with respect to said ring gear, releasable locking means adapted to retain said driving gear in engaged relation with said ring gear, means carried by said ring gear adapted at one point in its rotation to engage said releasable locking means to disengage it from relation with said driving gear, and means adapted to move said driving gear out of engagement with said ring gear upon release.
10. In a winding machine of the character described, a base, a ring support mounted upon said base for rotatably supporting the ring to be wound, a rotatable winding shuttle mounted in relation to said support adapted to wind material carried thereon about said ring, a ring gear mounted upon said base, means carried by said ring gear adapted to rotate said ring, a driving gear for rotating said ring gear, means slidably mounted upon said base supporting said driving gear and movable to engage and disengage said driving gear with respect to said ring gear, manually operable means adapted to move said driving gear support to engage said driving gear with said ring gear, releasable locking means adapted to retain said driving gear in engaged relation with said ring gear, means carried by said ring gear adapted at one point in its rotation to engage said releasable locking means to disengage it from relation with said driving gear, and spring means adapted to move said driving gear out of engagement with said ring gear upon release.
11. In a winding machine of the character described, a base, a ring support mounted upon said base for rotatably supporting the ring to be wound, a rotatable winding shuttle mounted in relation to said support adapted to wind material carried thereon about said ring, a ring gear mounted upon said base, means carried by said ring gear adapted to rotate said ring, a driving gear for rotating said ring gear, means movably mounted upon said base supporting said driving

5 gear and movable to engage and disengage said driving means with respect to said ring gear, driving means for said driving gear mounted on said base, and a universal and extensible driving connection between said driving means and said driving gear.

10 12. In a winding machine of the character described, a base, a ring support mounted upon said base for rotatably supporting the ring to be wound, a rotatable winding shuttle mounted in relation to said support adapted to wind material carried thereon about said ring, means movably mounted upon said base supporting said shuttle, a driving gear carried by said shuttle 15 support for driving said shuttle, driving means for said driving gear mounted on said base, a universal and extensible driving connection between said driving means and said driving gear, a ring gear mounted upon said base, means carried by said ring gear adapted to rotate said ring, a driving gear for rotating said ring gear, means movably mounted upon said base supporting said driving gear and movable to engage and disengage said driving means with respect to said ring gear, driving means for said driving gear mounted on said base, and a universal and extensible driving connection between said driving means and said driving gear.

20 13. In a winding machine of the character described, a base, a ring support mounted upon said base for rotatably supporting the ring to be wound, a rotatable winding shuttle mounted in relation to said support adapted to wind material carried thereon about said ring, a ring gear mounted upon said base, means carried by said ring gear adapted to rotate said ring; a driving gear for rotating said ring gear, means movably mounted upon said base supporting said driving gear and movable to engage and disengage said driving means with respect to said ring gear, releasable locking means adapted to retain said driving gear in engaged relation with said ring gear, means carried by said ring gear adapted

25 at one point in its rotation to engage said releasable locking means to disengage it from relation with said driving gear, means for moving said driving gear out of engagement with said ring gear upon release, means for driving said shuttle, clutch means for connecting and disconnecting said driving means, and a connection between said clutch means and said driving gear adapted to engage and disengage said clutch means upon engagement and disengagement of 30 said driving gear with respect to said ring gear.

14. In a winding machine of the character described, a base, a ring support mounted upon said base for rotatably supporting the ring to be wound, a rotatable winding shuttle mounted 15 in relation to said support adapted to wind material carried thereon about said ring, a ring gear mounted upon said base, means carried by said ring gear adapted to rotate said ring; a driving gear for rotating said ring gear, means movably 20 mounted upon said base supporting said driving gear and movable to engage and disengage said driving means with respect to said ring gear, releasable locking means adapted to retain said driving gear in engaged relation with said ring gear, means carried by said ring gear adapted at one point in its rotation to engage said releasable locking means to disengage it from relation with said driving gear, means for moving 25 said driving gear out of engagement with said ring gear upon release, means for driving said shuttle, clutch means for connecting and disconnecting said driving means, and a connection between said clutch means and said driving gear 35 adapted to engage and disengage said clutch means upon engagement and disengagement of said driving gear with respect to said ring gear, and manually operable means between said clutch means and said ring rotating means for manually 40 rotating said shuttle when said clutch means is disengaged.

DOMINIC J. HOLLERAN.
